UNITED STATES PATENT OFFICE.

JOHN C. BLUNDELL, OF BOSTON, MASSACHUSETTS, ASSIGNOR TO PNEUMATIC TEXTILE MACHINERY COMPANY, OF JERSEY CITY, NEW JERSEY, A CORPORATION OF NEW JERSEY.

PNEUMATIC DRIVER AND CUSHION FOR LOOM-SHUTTLES.

SPECIFICATION forming part of Letters Patent No. 717,965, dated January 6, 1903.

Application filed November 30, 1901. Renewed December 13, 1902. Serial No. 135,164. (No model.)

To all whom it may concern:

Be it known that I, JOHN C. BLUNDELL, of Boston, in the county of Suffolk and State of Massachusetts, have invented certain new and useful Improvements in Pneumatic Drivers and Cushions for Loom-Shuttles, of which the following is a specification.

My invention relates to new and useful improvements in pneumatic drivers and cushions for loom-shuttles; and its object is to drive the shuttle by the reed in both directions and to provide for the driving of the shuttle from one side to the other by compressed air and to cushion by air the shuttle at the end of the throw.

My invention consists of certain novel features hereinafter described, and particularly pointed out in the claims.

In the accompanying drawings, which illustrate a construction embodying my invention, Figure 1 is a perspective view, partly in section, of my pneumatic driver and cushion. Fig. 2 is a detail side view. Fig. 3 is a sectional view. Fig. 4 is a plan view. Fig. 5 is a sectional view. Figs. 6 and 7 are views of detail parts hereinafter described. Fig. 8 is a sectional view. Fig. 9 is a front view of the loom, showing my improved device located on both ends with the shuttle in position to be driven to the opposite end. Fig. 10 is a cross-sectional view through Fig. 9. Fig. 11 is a detail view of the head which drives the shuttle.

Like letters of reference refer to like parts throughout the several views.

My device consists of a base-plate A, by which it may be secured to the lay or lathe of the loom, and of a lower cylinder C. Within the cylinder B is arranged a plunger D, having a series of openings D' therethrough and having a shaft D² and a head D⁴, located around the shaft D³, which is also provided with a head D⁵, adapted to engage with the head D⁴, as hereinafter described, and both of said shafts D² and D³ pass through the cylinder-head D⁶ of the cylinder B. Located in the cylinder B forward of the plunger D is a piston E, fast on the shaft D³, and on said shaft at its extreme forward end is the head E², lo-

cated beyond the cylinder-head E', through which the shaft D³ passes. The forward end of the cylinder B is provided with a series of perforations B³, through which the air in the cylinder escapes upon the forward movement of the piston E. In the upper cylinder C is located the valve F⁵ for normally closing communication between the port B, through which compressed air enters from the pipe B', and the interior of the cylinder B. This valve, as shown in Fig. 5, is provided with a forwardly-projecting sleeve F⁴, in which is located the spring F³, and in said spring is the finger F² to prevent the spring F³ from buckling, and said finger is held in place by means of the nut F', which screws into the end of the outer sleeve F, which in turn is screwed onto the cylinder C. The opposite end of the valve F⁵ is provided with a sleeve F⁶, in which is located the spring F⁷, and within said coiled spring F⁷ is a finger F¹¹, adapted to keep the spring F⁷ from buckling, and located beyond said spring is the piston-head F⁸, having a shaft F⁹ projecting through the cylinder-head F¹⁰ of the cylinder C, and said piston and shaft are normally out of contact with the sleeve F⁶ by means of the spring F⁷, as shown in Fig. 1. This device is secured, as shown in Fig. 9, on the opposite ends of the lathe J, beyond the reed L of the loom H, and said lathe J is carried by the rocker-arms K, which are rocked by the rocker-shaft K', journaled in the end supports K², and said rocker-shaft may be operated by any suitable power.

In the operation of my device as the shuttle passes by the reed the lathe moves up and drives the filling against the warp or cloth, at which time the lathe J and co-operating parts are in the position shown in full lines, Fig. 10, and as the rocker-arms move to the position shown in dotted lines, Fig. 10, the shaft F⁹ strikes the projection K³ on one of the end supports K², and this upward movement of the shaft F⁹ causes the piston F⁸ to move up into contact with the sleeve F⁶ and compresses the spring F⁷ and closes the exhaust-port C², Fig. 1, and the continued movement of the piston F⁸ opens the valve F⁵ against the tension of the spring F³, and air

passes from the pipe B' through the port B² into the cylinder C and down through the port C' into the cylinder B, the parts previously described being in the position shown 5 in Fig. 3 as this operation takes place. This air passes into the cylinder B, as indicated in dotted arrows, Fig. 1, between the piston E and the plunger D and drives the piston E forwardly from the position shown in Figs. 1 10 and 5 to that shown in Fig. 8, and the air ahead of the piston E is forced out through the perforations B³ in the cylinder B. During this forward movement of the piston E the head D⁴ comes into contact with the head 15 D⁴ of the plunger D and moves said plunger forwardly until it reaches the position shown in Fig. 8 and closes the port C'. This forward movement of the piston E with its shaft D³ drives the head E² outwardly and causes 20 the shuttle M to be thrown to the opposite end of the lathe, where it is cushioned by a device similar in construction and operation to that shown and described at the right-hand end of the lathe or lay of the loom. During 25 this time the lathe has moved upwardly, and the shaft F⁹ has left contact with the projections K⁸, and the springs F⁷ and F⁸ operate to move the parts back into their normal positions, leaving the port C² open. The device 30 at the right-hand end of the drawing, Fig. 9, after this operation has its head E² in the outer position similar to that shown on the left hand of Fig. 9 and ready to receive and cushion the shuttle M, which is sent from the 35 left to the right in a manner identical for that described for sending it from right to left. As the shuttle M strikes the head E² it drives the shaft D³, with the piston E', rearwardly, and when the piston E comes in contact with 40 the plunger it forces said plunger backward; but inasmuch as the air has passed to the rear of the plunger D on the forward movement, as previously described, this plunger moves rearward only so fast as the air at the 45 rear of it can escape through the ports C⁵ until said ports are closed by the plunger D and then through the perforations D'. In the forward movement of the piston E the air exhausts freely from the ports B³, and as the 50 piston reaches the end of the cylinder-head which covers these ports the piston on its further travel is slowly cushioned, as the area of outlet from the air ahead of it is restricted by the port C⁴. The backward movement 55 of the piston E forces the air through the perforations D' of the plunger D and out through the ports C⁵, and when it comes into contact with the plunger D it moves it backward, and the air to the rear of the 60 plunger escapes through the port C⁵ until said port is closed by the plunger D, when the air escapes through the perforations D' out through the ports C' and C², so that the movement of the plunger rearwardly after it 65 covers the ports C⁵ forms a slower cushion, as the exhaust is retarded during this latter

movement. The head E² (shown in Fig. 11) is recessed to hold the rawhide filling N, which is countersunk at N' to receive the end of the shuttle and in perfect alinement with the way 70 of the loom and the center of the shuttle. By driving the shuttle on its center the liability of the shuttle jumping from the way is avoided, which liability is apt to occur in the present style of loom-shuttles where the 75 picker-sticks are used, owing to the fact that said picker-sticks strike the shuttles above their longitudinal center line, and by my arrangement the countersink in the rawhide wears evenly, for the reason that it is always 80 struck in the same place. The openings of the ports C² C⁴ are large enough to exhaust the air faster than is desired, and the screws C⁶ C⁷ are inserted projecting into said ports and open or close the ports, according to the 85 amount of cushion it is desired to obtain at the ends of the cylinders.

Having thus ascertained the nature of my invention and set forth a construction embodying the same, what I claim as new, and 90 desire to secure by Letters Patent of the United States, is—

1. In an apparatus of the character described, a cylinder, a source of compressed air, an inlet for the compressed air to the cylinder, a valve controlling said inlet, mechanism operated by compressed air for driving the shuttle, and means independent of said air-inlet-controlling valve for regulating the escape of air from the cylinder and thereby 95 cushioning said driving mechanism on its return stroke.

2. In an apparatus of the character described, a cylinder, a source of compressed air, an inlet for the compressed air to the cylinder, a valve controlling said inlet, mechanism operated by compressed air for driving the shuttle, and means controlled by said driving mechanism for regulating the escape of air from the cylinder and thereby 105 cushioning said driving mechanism on its return stroke.

3. In an apparatus of the character described, a cylinder, a source of compressed air, an inlet for the compressed air to the cylinder, a valve controlling said inlet, mechanism operated by compressed air for driving the shuttle, and means independent of the 115 said air-inlet-controlling valve and controlled by said driving mechanism for regulating the 120 escape of air from the cylinder and thereby cushioning said driving mechanism on its return stroke.

4. In an apparatus of the character described, a cylinder, a source of compressed 125 air, an inlet for the compressed air to the cylinder, a valve controlling said inlet, a piston operated by compressed air for driving the shuttle, a plunger operated by said piston and provided with perforations, and ports in 130 the cylinder through which the air at the rear of the plunger escapes until closed by

said plunger after which the air exhausts from the rear of the plunger through the perforations.

5. In an apparatus of the character described, a cylinder, a source of compressed air, an inlet for the compressed air to the cylinder, a valve controlling said inlet, a piston in said cylinder operated by compressed air for driving the shuttle, and a plunger in said cylinder operated by said piston for cushioning the shuttle.

6. In an apparatus of the character described, a cylinder, a source of compressed air, an inlet for the compressed air to the cylinder, a valve controlling said inlet, a piston in said cylinder operated by compressed air for driving the shuttle, a plunger in said cylinder operated by said piston for cushioning the shuttle, and means for producing a slow cushion at the end of the stroke.

7. In an apparatus of the character described, a cylinder mounted on the lathe, a source of compressed air, an inlet for the compressed air to the cylinder, a valve controlling said inlet and opened on the movement of the lathe in one direction, means for closing said valve upon the movement of the lathe in the opposite direction, mechanism operated by compressed air for driving the shuttle, and means independent of said air-inlet-controlling valve and controlled by said driving mechanism for regulating the escape of air and thereby cushioning said driving mechanism on its return stroke.

8. In an apparatus of the character described, a cylinder mounted on the lathe, a source of compressed air, an inlet for the compressed air to the cylinder, a valve controlling said inlet and opened on the movement of the lathe in one direction, means for closing said valve upon the movement of the lathe in the opposite direction, a piston in said cylinder and operated by compressed air for driving the shuttle, ports in the cylinder through which the air is exhausted from in front of the piston on the forward movement of the piston, and a port in the head of the cylinder through which the air slowly exhausts from in

front of the piston when said ports are closed by the piston.

9. In an apparatus of the character described, a source of compressed air, an inlet for the compressed air to the cylinder, a valve controlling said inlet, a piston in said cylinder and operated by compressed air for driving the shuttle, exhaust-ports at the forward and rear ends of the cylinder through which air escapes upon the forward and return movements respectively of the piston, means for cushioning the piston at the end of its forward stroke, and means independent of said air-inlet-controlling valve for regulating the escape of air from the cylinder and thereby cushioning the piston on its return stroke.

10. In an apparatus of the character described, a source of compressed air, an inlet for the compressed air to the cylinder, a valve controlling said inlet, a piston in said cylinder and operated by compressed air for driving the shuttle, exhaust-ports at the forward and rear ends of the cylinder through which air escapes upon the forward and return movements respectively of the piston, means for cushioning the piston at the end of its forward stroke, and means controlled by said piston for regulating the escape of air and thereby cushioning the piston on its return stroke.

11. In an apparatus of the character described, a cylinder, a source of compressed air, an inlet for the compressed air to the cylinder, a valve controlling said inlet, a piston in said cylinder and operated by compressed air for driving the shuttle, and means in said cylinder controlled by said piston for regulating the escape of air and thereby cushioning said piston on its return stroke.

In testimony whereof I have signed my name to this specification, in the presence of two subscribing witnesses, this 26th day of November, A. D. 1901.

JOHN C. BLUNDELL.
